LEVELING AND HOLDING DEVICE

Garland C. Young, Wichita Falls, Tex., assignor
of one-half to Joe B. Elder, Wichita Falls, Tex.

Application October 1, 1951, Serial No. 249,060

10 Claims. (Cl. 33—207)

1 This invention relates to improvements in leveling devices and more particularly to leveling devices for leveling or holding an object in a predetermined relation to the horizontal on any surface, whether the surface is level, irregular, or sloping.

Various leveling devices have been proposed heretofore, but these were of little use on irregular or sloping surfaces or when the object to be leveled was above or below the surface or in such close quarters that it could not be leveled or set with respect to the surface with which it was co-related.

In setting such objects as trunnions for door hinges, door checks and the like, it is often required that these be set so that the trunnion or pivot is in alignment with a trunnion or pivot point about that being set, and such installations are frequently set in floors that are rough or do not have their finish coat at the time the trunnion is set. Or, if the floor is finished, the installation of such trunnions, pivot points, door checks or hinges, becomes a very exacting procedure, as they must be properly spaced from the pivot point above, and the pivot point must be in axial alignment with the pivot point above. Also, the pivot point must bear a fixed relation to the finished floor regardless of whether the floor is level, rough or sloping.

An object of this invention is to provide a leveling device when holds a hinge, door check or other object to be set at a predetermined level or in an angular position with respect to the horizontal, regardless of the terrain or surface on which the device is to be used to set the hinge, door check or the like.

Another object of this invention is to provide a device for holding an object to be set in a level or fixed position with respect to the horizontal and to provide an opening therethrough to make the plumbing of the object possible with respect to a fixed point thereabove.

Still another object of this invention is to provide a leveling device having pairs of downwardly depending fingers for gripping and holding an object in a predetermined relation with the upper surface thereof.

A still further object of the invention is to provide a holding device for holding hinges, door checks and the like, which holding device is adjustable through a wide range, and which will enable the setting of hinges, door checks and the like at or below the surface.

Yet another object of the invention is to provide a leveling device that is simple in construc-

2 tion, inexpensive to manufacture, and that is easy and positive in operation.

An embodiment of this invention is illustrated in the accompanying drawing, in which:

Fig. 1 is a perspective view of the device taken from above and showing an end and a side thereof;

Fig. 2 is a sectional view taken of the line 2—2 Fig. 1 looking in the direction indicated by the arrows, and showing the device as resting on a concrete floor surface, with a trunnion member, shown in dashed outline, suspended in a recess within the concrete; and

Fig. 3 is a perspective view of one form of trunnion member from the top, showing an end and a side thereof.

With more detailed reference to the drawing, the numeral 1 designates a concrete floor having a recess or hole 2 formed therein. The device, as shown in Fig. 1, has a plate 3 which is of substantially T-shape. Screw members 4, 5, and 6 are provided, one at each end of the T-shaped frame member, and which screw members are provided with hand wheels 7, 8, and 9, respectively at their upper ends, and which screw members are pointed at 10, 11, and 12, at their respective lower ends. The screw members are provided with pointed lower ends for two reasons, first, to reduce the skidding of the leveling device, and secondly, the pointed lower ends of the screws allows for a more accurate leveling of the surface on which it is used if the surface is irregular or sloping, nor does the pointed lower end of the screws affect the ready placing of the device, as would be the case if the adjusting screws had large flat ends.

The stem 13 of the T-member has a central slot 14 throughout the greater portion of the length thereof, and the slots 15 and 16 are formed in the stem 13 on each side of the slot 14 and are parallel thereto. Bolts 17, 18, 19 and 20 pass through the slots 15 and 16 and have their upper ends threaded to receive the respective wing nuts 21, 22, 23, and 24. The lower end of each of these bolts is secured to the respective lateral projections 25, and 26, as by welding or the like. The projections 25 and 26 have pivot pins 27 and 28 passing therethrough and through a looped end of depending hooks 29 and 30, respectively, so as to form a hinge joint, as will best be seen in Fig. 2.

Each of the members 29 and 30 has a hole intermediate the ends thereof, a bolt 31 passes through each of these holes, and has a head on one end and a wing nut on the opposite end. A compression spring 33 is interfitted between the

depending hooks 29 and 30 so as to urge the hook members apart when the wing nut 32 on bolt 31 is loosened. The depending hook members 29 and 30 have inturned hooks or lips 34 and 35 formed on their respective lower ends so as to engage below a shoulder 36 of the object to be leveled or set, as will best be seen in Fig. 2.

The object being set, such as a hinge or a door check 37 may have an upstanding trunnion post 38, which must be aligned with a trunnion thereabove, as in the case of a door, whereupon, a plumb bob may be dropped from the center of the upper trunnion so as to align with the centering hole 39 on the trunnion post 38, therefore the plumb bob point must pass through slot 14 to 15 enable the correct alignment.

Operation

Preparatory to the setting or leveling of a door check, hinge, trunnion, or other object to be leveled or set, wing nuts 21, 22, 23, and 24 are loosened and moved the desired spaced distance apart longitudinally so as to accommodate the object to be leveled or set, then the wing nuts 32 are loosened so as to permit springs 33 to swing fingers 29 and 30 laterally outward until they are sufficiently wide apart to accommodate the object to be leveled or set. Whereupon, the object, such as a door trunnion or door check, 37 is then inserted between the fingers 29 and 30, then wing nuts 32 are tightened until the hook points 34-35 interengage below the outstanding shoulder 36 of the object being leveled, so as to support the object.

Then, with the object 37 supported by two pairs of fingers 29-30, the wing nuts 21, 22, 23 and 24 may be tightened to hold the object relatively rigid with respect to plate member 3, or if desired, before the screws are tightened, the object 37 may be moved longitudinally of the stem 13 of the T-shaped frame member, to the desired location before the last mentioned wing nuts are tightened. After the object 37 is secured in place and with the plumb bob or other device suspended from a point above, to a point above where the object 37 is to be located. Thus the position of the plate member 3 and the object 37 is determined, and the device can be moved into the proper position and aligned under the object in substantially vertical alignment.

With the plate 3 positioned so that the point on the object 37, such as alignment hole 39, is in alignment with the point of the plumb bob, hand wheels 7, 8, and 9 of the respective screws 4, 5, and 6 are turned until the upper surface of the door check or other object occupies the correct elevation with respect to the surface of the floor in which it is being set. As in the present case, Fig. 2, the surface of the object is shown to be level with the floor, whereupon, certain of the hand wheels 7, 8, or 9 may be turned to lower or raise the particular portion of the plate 3 until levels 40 and 41 indicate that the plate 3 is level both transversely and horizontally, and since the distance from the top of the plate 3 to the top of the hooks 34 and 35 is equidistant, and object of even thickness, resting thereon will be parallel to the surface of the plate 3.

When the surface of the plate 3 is leveled by levels 40 and 41, the surface of the object will also be level, and if the up-standing post 38 is vertical with respect to the top surface of the object 37 and in alignment with the center of the axis above, and the correct spacing therefrom,

the door check can be accurately and positively set to any predetermined specification, thus eliminating any trial and error method of setting.

After the object 37 has been suspended the correct spaced distance from the trunnion post or other point of reckoning from above, and with the door check or other object 37 suspended in hole 2, as is the usual practice, grouting cement 42 is filled into hole 2 and about door check or other object 37 to a point slightly below hooks 34-35, and with the object 37 suspended, it is left until the cement has hardened sufficiently to support the object 37, whereupon, wing nuts 32 are loosened until hooks 34-35 disengage from below shoulder 36 to permit the removal of the leveling device. As in the present illustration, the remainder of the hole 2 may be filled with cement so as to make a flush mounting, with the trunnion point or other point of reckoning positioned to the exact desired point, the object 37 is thus accurately leveled and held in that position until the cement has hardened, thus making the installation permanent in its proper aligned position.

While the device has been described in some detail with respect to the leveling of door trunnions, hinges and the like, it is to be understood that this has been set forth as a matter of example and as respecting one application of the device, but the inventor wants it to be understood that the present leveling device may be used in any field which requires the leveling of an object with respect to the horizontal, even though the adjacent surface may be level, irregular, or sloping.

It is also to be pointed out that while the invention has been illustrated and described in some detail in one embodiment thereof, it is to be understood that changes may be made in the minor details of construction, and adaptations made to particular installations without departing from the spirit of the invention as set forth in the appended claims.

Having thus described the invention, what is claimed is:

1. In a leveling device for holding an object in a predetermined position with respect to the horizontal, a frame member, a plurality of adjustable members mounted at spaced points about said frame member for raising and lowering said frame member with relation to said surface on which said adjustable members rest, levels positioned on said frame at right angles to each other for leveling said frame member, a pair of depending members having inturned hooks, means for adjustably connecting said depending members to said frame for longitudinal adjustment with respect to said frame members for holding said object horizontally a spaced distance below said frame member, and means for bindingly engaging said depending members laterally with said object.

2. In a leveling device for holding an object in a predetermined position with respect to the horizontal, a frame member, three adjustable screw members mounted at spaced points about said frame member for engaging a surface for raising and lowering said frame member with relation to said surface on which said adjustable screw members rest, levels positioned on said frame at right angles to each other for leveling said frame member, a pair of depending members having inturned hooks, screw means for adjustably connecting said depending members to said frame for longitudinal adjustment with

respect to said frame member for holding said object horizontally a spaced distance below said frame member and screw means for bindingly engaging said depending members laterally with said object.

3. In a leveling device for holding an object in a predetermined position with respect to the horizontal, a frame member, a plurality of adjustable screw members engaging said frame member and adjustable with respect thereto for raising and lowering said frame member, levels positioned on said frame at an angle with respect to each other for leveling said frame member, said frame member having a plurality of openings formed therein, one of said openings being so arranged as to permit taking measurements and plumbing therethrough, other of said openings having screw members therethrough to attachably secure depending members therebelow for holding said object a spaced distance below said frame member, and means for drawing said depending members together to bindingly engage said members with said object.

4. In a leveling device for holding an object in a predetermined position with respect to the horizontal, a frame member, a plurality of adjustable screw members engaging said frame member and being adapted to rest on a surface, said screw members being adjustable for raising and lowering said frame member with respect to said surface, levels positioned on said frame member at an angle with respect to each other, said frame member having a plurality of elongated slots formed therein, one of said slots being so arranged as to permit taking measurements and plumbing therethrough, the other of said slots having screw members therethrough to attachably secure depending members therebelow for holding said object a spaced distance below said frame member, and screw means for drawing said depending members together to bindingly engage said members with said objects.

5. In a leveling device for holding an object in a predetermined position with respect to the horizontal, a frame member, three adjustable screw members engaging said frame member and adapted to rest on a surface, said adjustable screw members being adjustable to raise and lower said frame member with respect to said surface, levels positioned on said frame member at an angle with respect to each other for leveling said frame member, said frame member having a plurality of parallel slots formed therein, one of said slots being adapted to taking measurements and plumbing therethrough, means for movably attaching depending members through the other of said parallel slots, said depending members each having an inturned hook on the lower end thereof, said depending members being hingeably mounted and suspended below said frame for holding said object a spaced distance therebelow, and screw members for drawing said depending members together to engage said object.

6. In a leveling device for holding an object in a predetermined position with respect to the horizontal, a frame member, a plurality of adjustable screw members threadably engaging said frame member and being adapted to rest on a surface, said screw members being adjustable for raising and lowering said frame member with respect to said surface, levels positioned on said frame member at right angles to each other for leveling said frame member, said frame member having a plurality of elongated aligned slots formed

therein, one of said slots being so arranged as to permit taking measurements and plumbing therethrough, the other of said aligned slots having screw members therethrough to attachably secure depending members therebelow for holding said object a spaced distance below said frame member, resilient means interposed between said depending members for urging said depending members apart, and screw means for drawing said depending members together to bindingly engage said object.

7. In a leveling device for holding an object in a predetermined position with respect to the horizontal, a frame member, three adjustable screw members threadably engaging said frame member and adapted to rest on a surface, said adjustable screw members being adjustable to raise and lower said frame member with respect to said surface, levels positioned on said frame member for leveling said frame member, said frame member having a plurality of parallel slots formed therein, one of said slots being so arranged as to permit taking measurements and plumbing therethrough, means for movably attaching depending members through the other of said parallel slots to said frame, said depending members having inturned depending members thereon, which hooks are hingeably mounted and suspended below said frame for holding said object a spaced distance therebelow, resilient means interposed between said depending members for urging said depending members apart, and screw members for drawing said depending members together to bindingly engage said object.

8. In a leveling device for holding an object in a predetermined position with respect to the horizontal, a frame member having a central slot formed therein for measuring and plumbing therethrough, a plurality of adjustable members mounted on said frame member and adapted to rest on a surface, said adjustable members each having the end thereof that contacts said surface pointed, said adjustable members being adjustable to raise and lower said frame in relation to said surface, levels positioned on said frame at right angles to each other for leveling said frame, pairs of depending members suspended below and adjustably connected to said frame which depending members have inturned lips for holding said object substantially horizontal a spaced distance therebelow, and screw means for bindingly engaging said depending members with said object.

9. In a leveling device for holding an object in a predetermined position with respect to the horizontal, a substantially T-shaped frame member, a plurality of adjustable screw members engaging said T-shaped frame member, the lower ends of said screw members being adapted to rest on a surface, said adjustable screw members being adjustable for raising and lowering said frame with respect to said surface, levels mounted on said frame member at an angle with respect to each other, said T-shaped frame member having a plurality of openings formed in the stem portion thereof, one of said openings being provided for measuring and plumbing therethrough, the other of said openings being adapted to have screw bolts pass therethrough for engaging a hinged member therebelow to secure said hinged member to said frame, a depending member hingeably connected to each of said hinge members, each of said depending members having an inturned hook thereon for engaging and holding said object a spaced distance below said frame member, and screw

members for drawing said depending members toward each other for engaging said object.

10. In a leveling device for holding an object in a predetermined position with respect to the horizontal, a substantially T-shaped frame member, a plurality of adjustable screw members threadably engaging said T-shaped frame member and the lower end thereof being adapted to rest on a surface, said adjustable screw members being adjustable for raising and lowering said frame member with respect to said surface, levels mounted on said frame member for leveling said frame member, said T-shaped frame member having a plurality of aligned slots formed in the stem portion thereof, one of said slots being provided for 15 measuring and plumbing therethrough, the other of said slots having screw bolts therethrough for engaging a member therebelow for adjustment along the length of said slots, said member there-

below having depending members hingeably connected thereto and each of said depending members having inturned hooks for engaging and holding said object a spaced distance below said frame member, resilient means for urging said depending members away from each other and screw means for drawing said depending members toward each other for engaging said object.
